(No Model.)

A. L. DUWELIUS.

Electro Magnetic Brake.

No. 242,615.

Patented June 7, 1881.

UNITED STATES PATENT OFFICE.

AUGUSTUS L. DUWELIUS, OF CINCINNATI, OHIO, ASSIGNOR TO HIMSELF,
L. W. GOSS, H. D. PECK, HUGO WALTER, AND FRANK R. MERRILL, ALL
OF SAME PLACE.

ELECTRO-MAGNETIC BRAKE.

SPECIFICATION forming part of Letters Patent No. 242,615, dated June 7, 1881.

Application filed April 8, 1881. (No model.)

To all whom it may concern:

Be it known that I, AUGUSTUS L. DUWELIUS, a citizen of the United States, residing at Cincinnati, Hamilton county, Ohio, have invented 5 new and useful Improvements in Electro-Magnetic Brakes, of which the following is a specification.

My invention relates to improvements in apparatus for the application of electro-magnetism to braking railway-trains and other machinery, its object being to obtain a more efficient mechanical utilization of a given electro-magnetic force, and to provide mechanism for its application adapted more perfectly to conditions of 15 practical use.

To this end my invention consists in the devices hereinafter described, in which the friction of a chain-armature wound upon a revolving magnet actuated by an electric current is applied to the ordinary braking system of railway-cars, interchangeably with the ordinary hand-brake.

My invention is embodied in mechanism illustrated in the accompanying drawings, in 25 which—

Figure 1 is a side elevation of a railway-car truck and braking apparatus to which my invention is applied. Fig. 2 is a detached view, enlarged, of a portion of the apparatus, showing 30 the electro-magnet, chain-armature, and winding-pulley. Fig. 3 is a plan view of the same. Fig. 4 is an axial section of the contact-rings by which the electrical connection is formed; and Figs. 5 and 6 are side and end elevations respectively of a modification of the chain-armature.

The letters in the drawings refer to parts described in the specification.

In the drawings, A designates the car-wheels, 40 B the axles, C C the usual brakes, e the brake-lever, b the rod connecting corresponding brakes of a truck, and a the brake-rod connecting the lever e with the brake-shaft, these parts constituting the main features of the ordinary hand-brake system, all of which I employ directly, excepting the connecting-rod a and the hand-wheel, the latter being retained as an alternative means of braking for emergencies.

For the application of the electro-magnetic force I attach rigidly to one of the car-axles an insulated metallic spool, D, forming the core of a polarizing helix or helices, h, by which flanges d, with which the spool is provided, are rendered magnetic by the passage of the 50 electric current through the helices, and caused to attract the bars e of a chain-armature, E, which is thereby wound upon the flanges by the rotation of the spool. The armature, being connected by intermediate appliances with 55 the brake-lever e, actuates the brakes. The spool D is preferably a cylinder of cast-iron or other suitable material, provided with flanges d and divided longitudinally into two parts for convenience of attachment to the axle, to 60 which it is rigidly secured by keys or otherwise, the parts being preferably soldered together when in position upon the axle to form a substantially homogeneous tube surrounding the same. The flanges d are formed with overlapping ends, as shown, through which suitable bolts are passed, thus securely holding the parts of the spool together. The helices h, wound upon the spool between contiguous 65 flanges, may be separate from each other and 70 provided with separate battery-connections, or connected in one substantially continuous coil throughout, the latter arrangement being preferred. The ends of the wires are carried out beyond the end of the spool and connected 75 with two grooved collars, F F, secured rigidly to, but insulated from, each other and from the axle, upon which collars two rings, f f, are fitted and provided with binding-posts, with 80 which connections are formed with the electrical generator. The rings may be prevented from rotating by chains or links connecting them with the body of the car, and are designed to preserve a constant electrical contact with their collars, through which the current is 85 transmitted to the revolving magnet D.

The chain-armature E consists of a number of bars, e, of iron, held by links e' at suitable distances apart and parallel to the axis of the spool D. The armature is suspended by loose 90 yokes y from the axle, or from collars provided upon the axle at either side of the spool D. The yokes are arranged to retain the end

bar of the armature with sufficient radial play in relation to the spool D to permit the bar to remain normally out of contact with the peripheries of the flanges *d*, but within the circumference of magnetic attraction, so that when the magnet is charged by the current this bar will be attracted and caused to adhere to the periphery of the flanges and revolve with the spool, thus drawing all the bars of 10 the chain-armature successively into contact upon the revolving flanges. The armature E terminates in one or more chains connected with a winding-drum, G, upon which the brake-chain is arranged to wind, and thus actuate 15 the brake-lever *c*, to which the chain is connected. For the purpose of multiplying the power the armature-chain is secured at its remote end to the periphery of a sheave or sheaves secured upon the drum-shaft *g*, the drum-shaft 20 and sheave forming a windlass, which is hung in suitable links, *g'*, from the bottom of the car, or otherwise secured, either horizontally or vertically, in suitable journal-bearings.

The bars *e* are preferably rectangular in section, and are journaled loosely in the connecting-links *e'*, so as to turn and adjust themselves properly to the face of the flanges. The flanges *d* may be re-enforced by disks of steel at the sides, as a means of preventing the wear caused 25 by the bars *e*; or removable tires of iron may 30 be used for the same purpose.

A modification of the chain-armature is shown in Figs. 5 and 6. In this the bars *e* are held parallel in radial slots in two disks, H, 35 arranged loosely upon the axle at the sides of the spool D. The disks are provided with hubs, upon which collars *i* are fitted, by which the disks are suspended from the car or truck body, practically out of contact with the axle

and the spool-magnet. The bars have sufficient radial play in their holding-slots in the disks to allow them to remain normally out of contact with the faces of the flanges *d* of the magnet but be attracted thereto by the magnetic force. 40

Having described my invention, I claim and desire to secure by Letters Patent—

1. In combination with a spool-magnet secured to and revolving with a railway car-axle or other revolving shaft, a chain-armature consisting, essentially, of one or more connected bars adapted to be drawn by magnetic attraction to the peripheries of the spool-flanges, and having suitable chain-connection with brake mechanism, as set forth. 45

2. In an electro-magnetic-brake apparatus, a spool-magnet adapted to be secured upon and to revolve with a car-axle or other shaft provided with flanges whose peripheral faces are the contact-surfaces for the armature, in 50 combination with an armature consisting of one or more bars arranged parallel to the axle and normally out of contact with the magnet, but to be drawn by magnetic force thereto and caused to revolve therewith, substantially as 55 specified.

3. In combination with a revolving spool-magnet, the chain-armature E, as constructed, consisting of rectangular bars *e*, connected by links *e'* at suitable intervals, in which the bars 70 are journaled, substantially as described.

In testimony whereof I have hereunto set my hand in the presence of two subscribing witnesses.

AUGUSTUS L. DUWELIUS.

Witnesses:

C. P. DOOLITTLE,
C. F. HESSER.
